UNITED STATES PATENT OFFICE

HARRY RODSTEIN AND ISIDORE NATHANSON, OF NEW YORK, N. Y.

DESIGN FOR A FOOTBOARD FOR A BEDSTEAD OR SIMILAR ARTICLE

Application filed February 20, 1933. Serial No. 47,272. Term of patent 7 years.

To all whom it may concern:

Be it known that HARRY RODSTEIN and ISIDORE NATHANSON, both citizens of the United States, and residents of New York city, in the county of Kings and State of New York, have invented a new, original, and ornamental Design for a Footboard for a Bedstead or Similar Article, of which the following is a specification, reference being had to the accompanying drawing, forming part thereof, in which :

Fig. 1 is a front elevational view of a bedstead footboard showing our new design, and Fig. 2 is a top plan view thereof.

We claim:

The ornamental design for a footboard for a bedstead or similar article, as shown.

Dated, New York city, February 9th, 1933.

HARRY RODSTEIN.
ISIDORE NATHANSON.
